ALBERT J. RICE AND CHARLES S. ADAMS, OF BUFFALO, NEW YORK.

BOTTLE-FILLING VALVE.

1,170,672.

Specification of Letters Patent. Patented Feb. 8, 1916.

Application filed April 4, 1908. Serial No. 435,144.

To all whom it may concern:

Be it known that we, ALBERT J. RICE and CHARLES S. ADAMS, citizens of the United States, residing at Buffalo, in the county of Erie and State of New York, have invented certain new and useful Improvements in Bottle-Filling Valves; and we do hereby declare the following to be a full, clear, and exact description of the invention, such as will enable others skilled in the art to which it appertains to make and use the same.

Our improved valve is particularly designed for bottling milk, and we very particularly aim to provide for the quick filling of the bottles and at the same time to prevent the spilling of the milk, and to make the devices for controlling the flow of the milk of small number of parts and of such a construction that they may readily be taken apart for cleaning and present no surfaces on which the milk can become clogged.

In the drawings which illustrate a specific type of valve embodying several features of improvement, Figure 1 is a central section of the improved valve showing it closed. Fig. 2 is a similar view showing the valve opened by a bottle and Fig. 3 is a section on line 3—3 of Fig. 6.

The bottle filling valves *f* comprise a threaded plug 1 adapted to be screwed in an appropriate threaded opening in the bottom of the milk tank *e*. Rising from this plug are the two supporting rods 2 which carry at their upper ends a head 3 having a central perforation, and intermediate the head and the plug a guide frame 4. Depending from the lower end of the plug is an open filling tube 5. Passing centrally through the whole structure and through the central perforation in the head 3 is a tube 6 having a small central passage and terminating at its upper end in a screw-threaded enlargement 7 which is screwed into the central perforation of the head 3 and may be adjusted and locked in position by the screw-cap 8. At the lower end of this tube is a closure 9 for the vent-tube, and it will be observed that by the construction shown the closure 9 is rigidly fixed in a definite position. Surrounding this tube 6 and having a considerably larger diameter is the vent-tube, or main air tube 10 which passes freely through an opening in the center of the guide-frame 4 and has at its upper end a shouldered nut 11 which retains between its shoulder and the guide-frame 4 a compression spring 12.

On this vent-tube 10 is formed, at an appropriate distance below the guide-frame 4, a flange 13 which by engaging with the under surface of the guide-frame 4 limits the extension of the spring 12 and the consequent upward movement of the vent tube 10. Telescoping on the lower end of the depending tube 5 and making a close fit therewith is the closing tube 14, having the flange 15 and carrying at its lower end the annular rubber stopper 16, adapted to sit the mouth of the bottle to be filled. Between the flange 15 on this closing-tube and the plug 1, is a coiled compression spring 17. The lower end of the vent tube 10 has a cone-shaped enlargement adapted to form a seat for the beveled lower edge of the closing-tube 14. As will be seen from the drawings the main air tube or vent-tube 10, and the auxiliary air tube 6, may both be removed from the filling-valve structure by unscrewing the parts 7, 8 and 11. The mode of operation of these parts will be understood from the examination of Figs. 1 and 2, the device being shown closed in Fig. 1 and open by the upward pressure of a bottle top in Fig. 2. It will be seen that when a bottle is pressed upwardly against the lower end of the filling-valve, the rubber stopper 16 fits snugly in the mouth of the bottle and as the bottle is further lifted the closing tube 14 is lifted and the spring 17 is compressed. During the first portion of the upward movement the spring 12 expands and lifts the vent-tube 10, thereby separating the lower end of the vent-tube from the closure 9 and opening it. When the flange 13 engages the guide-frame 4 the upward movement of the tube 10 is stopped and the further upward movement of the bottle lifts the opening tube 14 to open a free passage for the milk from the interior of the tank through the tube 5 into the bottle. During the filling of the bottle the air escapes freely through the vent-tube 10 which may be of quite sufficient diameter to freely vent the bottle and prevent frothing or churning of the milk. When the bottle is filled the milk will continue to flow up the inside of the vent-tube until it has reached a level in that tube equal to the level in the tank, and if means were not provided for preventing the down-flow of this milk in the vent-tube when the bottle was removed, the milk would be spilled. In the present construction, however, this is prevented, since as the bottle is removed

the spring 17 expanding moves down the closing-tube 14 until it closes against the conical enlargement of the lower end of the vent-tube, and then this vent-tube is moved 5 down until its lower end is closed by the closure 9 thereby preventing the down-flow of the milk and retaining it for discharge into the next bottle.

In the construction shown the closure 9 10 is supported by a tube having a small internal duct open to the atmosphere and to the bottle at all times, the object of this being to relieve the vacuum and allow the removal of the bottle from the lower end of 15 the plug, since it has been found that with certain types of stoppers making a close and rather deep fit, there is a tendency for this vacuum to cause the bottle to stick to the stopper and to be lifted from the crate 20 when the crate is lowered.

We consider this construction of valve of particular value for the reason that the passage for the milk, when it has been opened by the bottle, is entirely unobstructed, and 25 contains no shoulders or projections on which the milk can cake, and also the parts in the path of flow of the milk are reduced to a minimum, and all of the parts are substantial and may easily be separated from 30 one another for cleaning. It has, in our opinion, been demonstrated that the type of filling-valve having a depending tube for the passage of the milk from the tank into the bottle, together with a central vent tube, 35 is of great practical value, but this type of valve presents some difficulties in operation because of the fact that the milk rises in the vent-tube. If the vent-tube is made large, a corresponding quantity of milk is 40 spilled in this way, but, on the other hand, if the vent-tube is made small the air does not pass freely from the bottle and causes a frothing or churning of the milk and in filling the bottles the upper portion will be 45 filled with froth which must be allowed to settle or be shaken down before the bottle can be completely filled, thereby increasing materially the time necessary for the filling of the bottles. With the present construction 50 the passage for the outflow of the air is amply sufficient to prevent this churning or frothing of the milk, but at the same time the closure 9 prevents the down-flow of the milk which has arisen in the vent-tube until the valve has been opened for 55 the second time by a second bottle, in which case the milk flows into the bottle and is saved; and the second air tube 6 prevents the sticking of the bottle to the valve when 60 the main air tube is closed.

What we claim is:

1. A valve for bottle-filling tanks comprising an unobstructed filling tube depending from the bottom of the tank, an open frame rising in the tank above the tube, a

stem extending axially through the filling-tube and supported in a fixed position by the frame, a vent-tube movably supported in said frame and surrounding the stem, a lifting spring for said vent-tube, an enlargement on the lower end of the stem constituting a closure for the vent-tube, a closing sleeve, entirely outside of and telescoping on the filling-tube and spring-pressed downwardly to seat on the lower end of the vent-tube and to carry down the vent-tube into engagement with its closure, against the action of the lifting spring, and a stopper surrounding said sleeve and adapted to fit within the mouth of the bottle to be filled; substantially as described.

2. A valve for bottle-filling tanks comprising a filling-tube depending from the tank, an open frame rising in the tank above said tube, a stem containing an auxiliary vent passage extending axially through said filling tube and supported in a fixed position by said frame, a main vent-tube movably supported in said frame and surrounding the stem, an enlargement on the lower end of the stem constituting a closure for the main vent-tube, a closing sleeve telescoping on the filling tube and spring-pressed downwardly to seat on the lower end of the main vent-tube and to carry down said main vent-tube into engagement with its closure, and a stopper surrounding said sleeve and adapted to fit within the mouth of the bottle to be filled; substantially as described.

3. A valve for bottle-filling tanks comprising a filling-tube depending from the bottom of said tank, an open frame rising in the tank above said tube, a stem extending axially through said filling tube and supported in a fixed position by said frame, a vent-tube supported in said frame by a spring which tends to lift the vent-tube, a stop limiting the upward movement of the vent-tube, an enlargement on the lower end of the stem constituting a closure for the vent-tube, a closing sleeve telescoping on the filling-tube and spring-pressed downwardly to seat on the lower end of the vent-tube and to carry down said vent-tube into engagement with its closure against the action of the lifting spring, and a stopper surrounding said sleeve and adapted to fit within the mouth of the bottle to be filled; substantially as described.

4. A valve for bottle-filling tanks comprising a plug 1 screwed into the bottom of said tank, a filling-tube 5 depending from said plug, rods 2 rising from said plug and supporting a head 3, a stem 6 extending axially through the filling-tube and adjustably supported in fixed position in the head 3, a guide-frame 4, a vent-tube 10 supported from the guide-frame 4 by spring 12 which tends to lift the vent-tube, an enlargement

9 on the lower end of the stem 6 constituting a closure for the vent-tube, a closing sleeve 14 telescoping on the filling-tube 5 and spring-pressed downwardly to seat on the lower end of the vent-tube and to carry down said vent-tube into engagement with its closure, and a stopper 16 surrounding said sleeve and adapted to fit within the mouth of the bottle to be filled; substantially as described.

5. A valve for bottle-filling tanks comprising a filling-tube depending from the bottom of said tank, a vent-tube centered in the filling-tube, a lifting spring for said 15 vent-tube, a closure at the lower end of the vent-tube, a closing sleeve telescoping on the filling-tube and spring-pressed downwardly to seat on the lower end of the vent-tube and to carry down said vent-tube into 20 engagement with its closure against the action of the lifting spring, and a stopper surrounding said sleeve and adapted to fit within the mouth of the bottle to be filled, substantially as described.

25 6. In a bottle filler, a filling tube, an air tube, means for closing each of said tubes, and a second air tube in open communication with the bottle at all times.

7. In a bottle filler, a filling tube having

a discharge opening for the liquid, an air 30 tube for discharging the air from the bottle, means adapted to close the liquid outlet and said air tube, and a second air tube open to the atmosphere and to the bottle at all times.

8. In a bottle filler, a filling tube, a main air tube, means for closing each of said tubes, and a second air tube of less capacity than the main air tube in open communication with the bottle at all times.

9. In a bottle filler, a filling tube having a discharge opening for the liquid, a main air tube for discharging air from the bottle, means adapted to close the liquid outlet and the main air tube, and a second air 45 tube of less capacity than the main air tube in open communication with the bottle at all times.

In testimony whereof we affix our signatures in presence of two witnesses.
